Thomas House ATTORNEY

UNITED STATES PATENT OFFICE.

AUSTIN D. BRIXKEY, OF NEW YORK, N. Y., ASSIGNOR TO ORDINATOR COMPANY, INC.,
A CORPORATION OF NEW YORK.

MULTIPLE SHADE-ROLLER.

1,377,461.

Specification of Letters Patent. Patented May 10, 1921.

Application filed August 15, 1917. Serial No. 186,287.

To all whom it may concern:

Be it known that I, AUSTIN D. BRIXKEY, a citizen of the United States, residing at city, county, and State of New York, have invented new and useful Improvements in 5 Multiple Shade-Rollers, of which the following is a specification.

This invention relates to the structure and support of rollers for window shades.

10 It is often desirable to provide several shades for a large window, or for a number of windows close together, so that the covering of the different window areas may be controlled independently. This is notably 15 the case in connection with a class of window structures which have come largely into use in connection with concrete and other buildings, namely that type where the glass panes are secured in a metal frame including 20 fenestra windows, which has the material of the wall cast about it or is otherwise immovably secured therein. With such structures the opening of a fenestra window would interfere with the operation of the 25 shade for all parts of the window if one shade extended across the entire window. Independence of control of the covering of different parts of the window may be effected so that the opening of a fenestra window 30 will not interfere with the whole window area, by dividing the shade into several. In the type of window referred to, however, there is scant means for securing shade supporting brackets, except at the marginal 35 frame of the entire window, and furthermore the multiplicity of brackets required for supporting a number of shade rollers, would be unsightly.

It is the main object of the present invention 40 to provide multiple shade rollers whereby division of control of the window areas will be secured, but which shall ordinarily require support only at the sides of the entire window, which shall present a neat 45 appearance and be simple in construction. This is accomplished by mounting a plurality of independently operable shade rollers of the desired dimensions upon a rod which may extend from one side of the window to 50 the other.

A further object of the invention is to provide improved structures of shade rollers.

Other and ancillary objects of the invention will appear hereinafter.

In the accompanying drawings which 55 illustrate the invention,

Figure 1 is a front elevation of a window to which the improved shade structure is applied;

Fig. 2 is a view on an enlarged scale 60 partly in section and partly in elevation of the shade roller structure of Fig. 1, the structure being partly broken away in this figure;

Fig. 3 is a section on the line 3—3 of Fig. 65 2, and

Fig. 4 is a section on the line 4—4 of Fig. 2.

Referring to the drawings within the frame 1 is mounted a window comprising 70 fenestra windows 2 and 3. This is a type of window extensively made use of in concrete buildings, the pane holding frame being made of metal and immovably mounted in the concrete wall, ventilation being controlled by the opening and closing of the 75 fenestra windows.

The rod 4 extends continuously across the window and is supported in brackets 5 and 6 secured to the frame and of a structure 80 as is well known in connection with the support of Hartshorn shade rollers. Thus the bracket 5 has a squared recess for receiving a squared projection from the rod 4 while the bracket 6 has a round aperture for receiving a round pintle at the other end of the rod.

The rod 4 is shown as hollow, that is as a tube in the ends of which are secured the plugs 7 and 8. The tube forms a stiffer 90 structure than a solid rod so that the tendency to sag, in long lengths, is more effectively opposed. The plug 7 carries the squared projection 9 for entering the squared recess of the bracket 5 to prevent turning of the rod 4, while the plug 8 has the round projection 10 to enter the aperture in the bracket 6.

Upon the rod 4 are rotably mounted the separate rollers carrying shades 11, 12, 13, 100 14 and 15 which are independently operable so that the several shades may be raised and lowered independently.

Each of the rollers comprises a shell or tube 16 on which the shade is secured and 105 rolled after the usual manner of shade rollers. The shell is fixed to disks 17 and 18 rotatably mounted on the rod 4, by

screws 19 and 20. The disks nearest the ends of the rod have hubs 21 and 22 adapted to bear against flanges 23 and 24 on the plugs 7 and 8 to properly space the end 5 rollers from the ends of the rod. Adjacent ends of the rollers intermediate the ends of the rod are suitably spaced from each other by means of hubs as 25 and 26. Preferably these hubs extend beyond the ends of the 10 shells of the rollers so that a clearance space as 27 is formed between their ends. A spring 28 tends to turn the disk 18 together with the disk 17 and the shell 16 about the rod 4 in a direction to roll up the 15 shade. As will be seen, this spring is coiled about the rod and has one end 29 secured to the rod by passing it through holes 30 and 31 therein, and clinching the end of it. The other end of the spring is 20 secured to the disk 18 by passing it through a hole 32 in the disk and turning up the end 33. The roller is held against turning on the rod 4 by means of dogs 34 and 35 pivoted on the disk 17 and adapted to 25 engage in recesses 36 and 37 in the rod 4. The apertures are of such size with relation to the dogs, that when the roller turns slowly, the upper dog will drop into an aperture and arrest its rotation; while on the 30 other hand the dogs are made of such weight that when the roller rotates at a comparatively high rate of speed, their inertia and centrifugal force prevent them from dropping into the aperture and consequently the 35 rotation of the roller is not arrested. The object of having apertures 36 and 37 on opposite sides of the rod 4, is to enable it to be installed in either of two positions 180° apart, but the squared end 9 and its coöperating recess in the bracket, will not permit 40 it to be installed in any intermediate position, it being understood that the squared end is of greater dimension in one direction than in the other, as is customary with the 45 squared pintles of shade rollers.

It will be observed that the shades may be made of different desired widths, so that various portions of the window may be independently covered or uncovered; also it 50 will be seen that where the opening of the fenestra windows interferes with the drawing down of the shade over them, this does not prevent the operation of the shades covering other portions of the window. If the 55 window were covered by a single shade extending across it, the opening of a fenestra window would interfere with the adjustment of the shade over the entire window.

It will further be observed that the structure of roller provided is very easy of adjustment and assembly. The tube constituting the rod 4 may be cut to any length desired and the necessary bracket attaching means secured to its ends. The rollers can 60 then be mounted upon the rod by sliding

a disk as 17 thereon, this carrying the stop dogs, as described. The spring and other disk may then be threaded on the rod and finally the shell 16 may be threaded over the disks and secured thereto by the screws 70 as 19 and 20. A similar operation serves to assemble the next roller and so on throughout the length of the structure. While the invention has been illustrated in what is considered its best embodiment, it 75 may be embodied in other structures without departing from its spirit and is not therefore limited to the structure shown in the drawings.

What I claim is—

1. The combination with a rod of brackets supporting said rod and a plurality of shade rollers mounted on said rod and rotatable about the same. 80
2. The combination with a tubular rod 85 of brackets supporting said rod and a plurality of shade rollers mounted on said rod and rotatable about the same.
3. The combination with a rod of brackets supporting said rod, a plurality of shade 90 rollers rotatably mounted on said rod and means for spacing said rollers along said rod.
4. The combination with a rod of brackets for supporting the same and a plurality 95 of rollers rotatably mounted on said rod, said rollers having abutting hubs extending beyond the circumferential surfaces of the rollers.
5. The combination with a rod of a plurality of shade rollers rotatably mounted thereon, each of said rollers comprising disks and a shell about said disks, springs interposed between said rod and each of said rollers, said springs tending to turn the rollers on the rod and means for holding the rollers against rotation, said disks having hubs extending beyond the circumferential surfaces of the rollers and abutting against each other to space the rollers along the rod. 100
6. The combination with a rod of a plurality of shade rollers rotatably mounted on said rod, springs tending to rotate said shade rollers, each of said shade rollers having a dog pivoted thereto and adapted to 115 engage with an aperture in said rod.
7. The combination with a tubular rod of a plurality of shade rollers rotatably mounted thereon, each of said rollers comprising disks and a shell thereon, springs tending to rotate said rollers, each of said 120 rollers having a dog pivoted on one of its disks and adapted to engage with an aperture in said rod; plugs secured in the ends of said rods and comprising projections for 125 engaging supporting brackets, at least one of said projections being rectangular in cross section, and said plugs further comprising flanges limiting the end-wise movement of said rollers, said disks having hubs 130

extending beyond the circumferential surfaces of the rollers and abutting against each other to space the said rollers from each other.

5. 8. The combination with a rod of brackets supporting said rod and a plurality of shade rollers placed end to end along said rod and rotatable about said rod.

9. The combination with a rod of brackets supporting said rod, a plurality of shade

rollers arranged end to end along said rod and being independently rotatable about said rod, centrifugally operated means for each roller for preventing relative rotation of the roller and rod and means for rotating 15 the roller about the rod.

In testimony whereof I have signed this specification this 13th day of August 1917.

AUSTIN D. BRIXEY.
